UNITED STATES PATENT OFFICE.

VOLNEY W. MASON, OF PROVIDENCE, RHODE ISLAND.

ELEVATOR.

SPECIFICATION forming part of Letters Patent No. 311,504, dated February 3, 1885.

Application filed June 17, 1884 (No model.)

To all whom it may concern:

Be it known that I, VOLNEY W. MASON, of Providence, in the county of Providence and State of Rhode Island, have invented a new 5 and useful Improvement in Elevators, of which the following is a full, clear, and exact description.

My improvements relate to hand and power elevators; and the invention consists in mechanism for multiplying the power combined with hoisting-chains and a balance-weight, as hereinafter described and claimed.

Reference is to be had to the accompanying drawings, forming a part of this specification, 15 in which similar letters of reference indicate corresponding parts in both the figures.

Figure 1 is an elevation of an elevator of the improved construction, and Fig. 2 is a plan view of the same.

Upon the cross-timbers at the top of well A is a shaft, *a*, carrying two chain or sprocket wheels, *b b*, and upon one end of the shaft is a large wheel or pulley, *f*, having a grooved periphery. On a short counter-shaft at one 20 side of shaft *a* two chain-wheels, *c c*, are attached. The chains *d d* from the car B pass over the chain-wheels *b* on shaft *a* to and over the wheels *c*, and have a balance-weight, *e*, attached to their ends, so that the car is sustained, or nearly so, by the weight at all times. 25 An endless hand-rope, *g*, passes around wheel *f* and down into the well, one side going through the car, so that the operator, by drawing upon the rope, turns the wheel *f* and shaft, and the chain-wheels *b* having a hold on the 30 chains the car is raised.

h is a brake-lever provided with a shoe tak-

ing against wheel *f*. From the lever a rope, *i*, extends downward in position for being grasped to operate the brake for stopping the 40 car or regulating its descent. The rope also extends upward from the lever over a pulley and carries a weight, *k*, which acts to draw back the brake.

When steam or other power is to be used 45 for raising and lowering the car, the wheel *f* will be replaced by any suitable gearing.

By using the large wheel *f* on the shaft carrying the small chain-wheels the power is multiplied, and, the car being balanced, the work 50 of raising it is comparatively light.

Having thus described my invention, I claim as new and desire to secure by Letters Patent—

1. In an elevator, the hoisting mechanism consisting of shaft *a*, chain-wheels *b c*, and 55 hand-rope wheel *f*, combined with chains *d* and balance-weight *e*, substantially as described.

2. In an elevator, the combination, with the suspension-chains, of chain-wheels *b b* on the 60 operating-shaft *a*, substantially as described.

3. The brake-lever *h* and rope *i*, combined with the operating-wheel *f*, said rope being connected to said lever and passed over a pulley, with a weight, *k*, attached to one end, and 65 with its other end extended down for convenient manipulation of the operator, whereby the same rope or medium is adapted to apply and release the brake, substantially as described.

VOLNEY W. MASON.
